Des. 189,837
Patented Mar. 7, 1961

189,837

MOBILE TRAFFIC SIGN

Harold T. Atwood, 11129 Eggleston Ave., Chicago, Ill.

Filed Jan. 5, 1960, Ser. No. 58,941

Term of patent 14 years

(Cl. D72—1)

Fig. 1 is a front elevational view of a mobile traffic sign showing my new design;

Fig. 2 is a side elevational view thereof;

Fig. 3 is a top plan view thereof; and

Fig. 4 is a bottom plan view thereof.

I claim:

The ornamental design for a mobile traffic sign, as shown.
